(57) CLAIM

We claim the ornamental design for buffet and china cabinet, as shown and described.

DESCRIPTION

FIG. 1 is a perspective view of a buffet and china cabinet according to an embodiment of the invention.

FIG. 2 is a front elevational view of a buffet and china cabinet according to an embodiment of the invention.

FIG. 3 is a side elevational view of a buffet and china cabinet according to an embodiment of the invention. The view from the opposite side being a mirror image thereof; and, FIG. 4 is a top plan view of a buffet and china cabinet according to an embodiment of the invention.

The dashed lines represent environmental elements only and form no part of the claimed design.
